FEED MECHANISM

Daniel Gurney, Waynesboro, Pa., and Conrad L. Ott, Detroit, Mich., assignors to Landis Tool Company, Waynesboro, Pa., a corporation of Pennsylvania

Application February 24, 1937, Serial No. 127,550

7 Claims. (Cl. 51—165)

Our invention relates to a feed mechanism for grinding machines or other machine tools.

It is an object thereof to provide a feed mechanism of the pawl and ratchet type which is actuated independently of any traverse movement between the work and wheel.

A further object is to provide a feed cam having a plurality of lobes, one or more of which may be provided with means for varying its lift.

10 A further object is to provide means whereby the cam follower may transmit impulses only from preselected lobes on the feed cam.

A further object is to provide means for automatically starting said feed mechanism when the 15 headstock spindle begins to rotate.

A further object is to provide means for automatically changing from a roughing feed to a finishing feed.

Our invention consists essentially of a motor 20 driven multi-lobe cam operably connected to a pawl and ratchet type feed mechanism.

Figure 1 is a plan view of a grinding machine in which my invention is incorporated.

Figure 2 is a front elevation of our device partly 25 in section.

Figure 3 is a partial front elevation showing the mechanism in finish feed position.

Figure 4 is a diagrammatic sketch of the control mechanism of our invention.

30 On the drawings Figures 1 and 2, numeral 10 indicates the bed of the machine. The carriage 11 is mounted on said bed. The wheel support 12 is mounted on said carriage movable in a direction transverse to the direction of movement of said carriage. The grinding wheel 13 is rotatably mounted on said wheel support. The piston 14 in cylinder 15 is mounted on carriage 11.

35 An elongated piston rod 16 is partially threaded to run in nut 17, which is attached to wheel support 12. An adjustable stop 18 limits the range of movement of said piston. Said piston provides a rapid feed or positioning movement of the grinding wheel. The hand wheel end of the feed screw is splined to permit relative axial movement between the parts. The grinding or slow feed is provided by pawl and ratchet operated hand wheel 19. The ratchet 20 is actuated by pawl 21, which consists of an arm to which is removably attached a hardened strip 22 for engaging the ratchet teeth. The said pawl is pivotally mounted on another arm 23, which in turn is pivotally mounted on carriage 11 at a point 24 under the hand wheel 19. A spring 25, one end of which is attached to the pawl 21, and the other 40 to arm 23, urges strip 22 into operative engage-

ment with the teeth of ratchet 20. An upright element 26 carries an adjusting screw 27, which acts as a stop to the idle movement of pawl 21. Pawl 21 and arm 23 carry stop elements 28 and 29, respectively, which are identical in shape. 5 When strip 22 is in contact with ratchet 20 the stops 28 and 29 are slightly out of alignment, with stop 28 in advance of stop 29 in the direction of screw 27. During the idle movement stop 28 engages screw 27 and the pawl 21 is given a 10 slight rotating movement until stop 29 engages said screw, at which time the stops are in alignment and further relative movement between them is prevented. This slight rotary movement of pawl 21 is sufficient to lift strip 22 out of contact with ratchet 20.

One end of a link 31 is rotatably attached to arm 23, the other end is supported by a link 32 which is suspended from the armature 33 of the solenoid 34. This solenoid is mounted in an 20 inverted position in a housing 35. Intermediate the ends of said link 31 are a shoulder 36 and a lug 37 which carries a screw 38. This screw is adjustable relative to shoulder 36. A spring 39 one end of which is attached to link 31, and 25 the other to housing 35, urges said link to the right. This movement is limited by stop screw 27. Said link is moved in the opposite direction by an arm 40 keyed to a shaft 41. Said arm carries a pin 42 which projects laterally therefrom into the path of movement of either shoulder 36 or screw 38. A second arm 43 is also keyed to the shaft 41 and carries a roller follower 44. A spring 45, having one end attached to arm 43 and the other to a housing 72, holds said 30 roller in contact with a multilobe cam 46. Said cam is secured to a shaft 47 in housing 72 and said shaft is driven through suitable gearing by a motor 48. One or more of the lobes of said cam may be made adjustable by inserting screws 49 40 therein.

It is desirable to have pawl 21 in the withdrawn position when feed motor 48 stops. To accomplish this a switch 50 is mounted in such a position relative to the cam 46 that it will be opened when the roller 44 is at a low point on the cam. Said switch may be placed in a branch line 51 from the normally open contact of switch 55. Said element 26, also, carries an arm 30, which extends therefrom and contacts with the periphery of hand wheel 19 and acts as a brake thereon, preventing said hand wheel from acting as a fly wheel. Said arm also acts as an indicator for the graduations on said hand wheel. 55

Operation

The operator moves the wheel carriage longitudinally by means of lever 75 to place the grinding wheel inside the work. In response to this movement, cam 51 on said carriage closes a switch 52 which is the supply line to the headstock motor 50. The supply line consists of two wires 53 and 54. All the electrical control mechanism is supplied from this source and line 54 through its branches 54a, 54b and 54c is the common return line. Upon closing the switch 52, the headstock motor 50 is started. At the same time feed motor 48 is started through two pole relay 55 which is in normal position as shown. Movement of the carriage is utilized as described in Gurney Patent 2,064,427 granted December 15, 1936, to direct a supply of fluid under pressure to line 56 and valve 57. This valve may be shifted in one direction by spring 58 and in the other direction by solenoid 59, to direct fluid under pressure to one side or the other of piston 14. In the position shown in Figure 4, solenoid 59 is de-energized and valve 57 will direct fluid under pressure through passage 60 to cylinder 15 and shift piston 14 to move the grinding wheel 13 into contact with the work piece. The switch 52 is also effective through the switch 55 shown in normal position, to start feed motor 48; said motor through a suitable transmission mechanism rotates feed cam 46 which acts through a follower 44 and associated parts described above to deliver feed impulses to wheel feed hand wheel 19 through pawl 21 and ratchet 20. With the parts in the position shown in Figure 2, each lobe of the cam actuates ratchet 20 so that said ratchet receives six impulses for every revolution of the cam.

The progress of the grinding operation may be controlled by any suitable sizing device. We prefer to use the type disclosed in the above mentioned Gurney patent, and, also, in Balsiger Patent 2,001,447, granted May 14th, 1935. A portion of one of these devices sufficient to understand its function in this application is shown in Figure 4. It consists of a section of a manometer tube 63 having a series of electrical contacts, 64, 65 and 66, which may be connected through a body of mercury 67 or other electrically conductive substance.

As the grinding operation proceeds the mercury rises in the tube as described in the above mentioned patent until contacts 64 and 65 are both covered, thus completing a circuit to solenoid 34 and line 54, 54a and 54c. This solenoid upon being thus energized acts through link 32 to lift arm 31 so that pin 42 will contact screw 38 instead of shoulder 36. The difference in position between the shoulder and the screw may be varied so that only those lobes having a high lift will be effective to actuate ratchet 20. The arm 40 will be oscillated by the other lobes but the movement will not be great enough to cause pin 42 to engage and move screw 38. Even those lobes having a high lift will transmit a shorter impulse to the feed pawl. Thus, feed impulses will be reduced in both frequency and magnitude thereby providing an extremely fine feed movement for the grinding wheel. The grinding operation continues until a further pre-determined size is reached when the mercury engages contact 66 energizing relay coil 68. Said coil operates the relay contacts to open the circuit to the feed motor 48 and to close the circuit to the timing mechanism 69, thus stopping the feeding movement

and setting in motion the mechanism for separating the wheel and the work. When the circuit to the timing mechanism is closed current also passes through branch line 81 to keep motor 48 running until cam 46 has reached a position to permit withdrawal of pawl 21. At this point one of the lobes of said cam operates switch 80 to stop said motor. If necessary a dynamic brake 82 of any suitable type may be utilized to stop the feed motor and cam more quickly. After a pre-determined interval said timer will close switch 70 to energize solenoid 59. Said solenoid will then shift valve 57 to a position to direct fluid under pressure to the right hand end of the cylinder 15, move piston 14 to the left end, and thus back off wheel 13 from the work. The work and wheel may then be separated axially and the separating movement will be effective through cam 51 to open the circuit to the headstock motor 50 through switch 52.

Various changes may be made in our device without departing from the spirit of the invention, therefore, we do not wish to be limited to the structure disclosed in the specifications and drawings but only as set forth in the appended claims.

We claim:

1. In a device of the kind described, a wheel support, a work support, mechanism for causing a relative feeding movement between said supports, a multiple lobe cam for causing intermittent movement of said feed mechanism, means for driving said cam, and means for rendering one or more of said lobes ineffective to operate said feed mechanism.

2. In a device of the kind described, a wheel support, a work support, mechanism for causing a relative feeding movement between said supports, a multiple lobe cam for causing intermittent movement of said feed mechanism, means for driving said cam, means for rendering one or more of said lobes ineffective to operate said feed mechanism, and means for varying the effective lift of one or more of said lobes.

3. In a device of the kind described, a work support, a wheel support, mechanism for causing a relative feeding movement between said supports, a cam for actuating said mechanism, a separate motor for driving said cam, and means for varying the magnitude and frequency of the feed impulses while maintaining a constant speed of said motor.

4. In a device of the kind described, a work support, a wheel support, means for effecting a feeding movement between said supports, mechanism for actuating said feeding means comprising a rotatable cam and means for rotating same, and means responsive to a change in size of a work piece for varying the magnitude and frequency of the feed impulses caused by said cam independently of said rotating means.

5. In a device of the kind described, a wheel support, a work support, mechanism for causing a relative feeding movement between said supports, a multiple lobe cam for causing intermittent movement of said feed mechanism, means for adjusting one or more of said lobes to provide a greater lift than the rest, automatic means for rendering the unadjusted lobes ineffective to operate said feed mechanism whereby to reduce the frequency of feed impulses.

6. A feeding mechanism for a machine tool including a tool support, a work support, mechanism for causing a relative feeding movement between said supports, means for causing intermittent movement of said feed mechanisms, including a

multiple lobe cam, means for adjusting one or more of said lobes to provide a greater lift than the rest, and automatic means to transmit feed impulses from said cam which correspond to the difference in lift between the adjusted and the unadjusted lobes.

7. A grinding machine comprising a wheel support, a work support, a feed mechanism for effecting a relative feeding movement between said supports including a pawl and ratchet mechanism,

means for actuating said pawl and ratchet mechanism including a multiple lobe cam, part of the surface of said cam causing engagement between said pawl and ratchet and another part of said cam permitting separation of said pawl and ratchet, a motor for driving said cam and means for stopping said motor when said pawl and ratchet are separated. 5
